UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-DRAWING MACHINE.

956,885.

Specification of Letters Patent.

Patented May 3, 1910.

Application filed August 30, 1909. Serial No. 515,262.

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Drawing Machines, of which the following is a specification, accompanied by drawings forming a part of the same, in 10 which—

Figure 1 represents a side elevation of a wire drawing machine embodying my present invention. Fig. 2 is a plan view of the same with the wire drawing block removed. 15 Fig. 3 is a side elevation of a wire drawing machine showing a modification of my invention, and Fig. 4 is a plan view of the same.

Similar reference letters and figures refer 20 to similar parts in the different views.

My present invention relates to that class of wire drawing machines in which a rotating block is employed, whereon the wire is wound as it is drawn through a reducing 25 die, said rotating block having a clutch connection with a vertical shaft through which rotary motion is communicated to the block, and the object of my present invention is to provide a simple and effective means where- 30 by the rotating block may be readily thrown into and out of engagement with the driving power, and I accomplish this object by the construction and arrangement of parts as hereinafter described and pointed out in 35 the annexed claims.

Referring to the accompanying drawings, 1 denotes the framework of the machine, 2 a rotating wire drawing block loosely mounted upon the upper end of a vertical 40 shaft 4 and connected therewith by a clutching mechanism '3, 3^a. The vertical shaft 4 is driven from a horizontal shaft 5 by means of beveled gears 6 and 7, in the usual manner of wire drawing machines of this class.

45 The under side of the wire drawing block is provided with an annular track 8, beneath which are friction rolls 9, 9 carried in the arms 10, 10 of a yoke 11, which is pivotally supported in bearings 12, 12 in the frame- 50 work of the machine. The yoke 11 is pro-

vided with an arm 13 capable of being depressed, in order to rock the yoke 11 and raise the friction rolls 9, 9, for the purpose of lifting the wire drawing block on the vertical shaft 4, in order to disengage the 55 clutching mechanism 3, 3^a. The free end of the arm 13 is pivotally connected by means of a link 14 with a radial arm 15 on a rocking shaft 16, which carries at its outer end a two-armed foot treadle 17, said radial arm 60 15 and link 14 forming a toggle-joint connection between the shaft 16 and the free end of the arm 13.

The arm 13 is connected with the fixed framework of the machine by means of a spiral spring 18, with its tension exerted to depress the arm 13 and raise the friction rolls 9, 9 in order to throw the clutching mechanism 3, 3^a out of engagement and stop the rotation of the wire drawing block 2. By 70 depressing the end 19 of the two-armed foot treadle, the toggle-joint is thrown into the position shown in Fig. 1, with the end 19 of the foot treadle 17 against a fixed stop 20 on the framework of the machine, and with the 75 pivot 21, connecting the link 14 and arm 15, carried just past a straight line joining the axes of the shaft 16 and the pivot 22 connecting the link 14 and the arm 13, so that the tension of the spring 18 will hold the 80 toggle-joint in position, with the free end of the arm 13 substantially at its highest point to hold the friction rolls 9, 9 in their lowest position, and with the clutching mechanism 3, 3^a in engagement. 85

When it is desired to stop the rotation of the wire drawing block 2, the left hand end 23 of the two-armed foot treadle 17 is depressed sufficiently to carry the pivot 21 past the line connecting the axes of the rocking 90 shaft 16 and the pivot 22, when the spring 18 will instantly act to throw the toggle-joint into the position indicated by broken lines 24, and sufficiently past the center to elevate the friction rolls 9, 9 and raise the wire drawing block on the vertical shaft 4 to throw the clutching mechanism out of engagement. 95

Referring to Figs. 3 and 4, I have shown a modification in the embodiment of my in- 100

vention, which consists in interposing between the link 14 and the free end of the arm of the lifting yoke a short arm 25 and a bent link 26, instead of connecting the link 14 directly to the free end of the arm of the lifting yoke, as shown in Figs. 1 and 2. The arm 25 is pivoted at one end 25^a to a fixed bracket 27, and its free end is pivotally connected to both the link 14 and to one end of the bent link 26, which is connected at its other end to the end of an arm 28 extending from a swinging yoke 29 having friction rolls 30, 30, which lift the wire drawing block 2 as the free end of the arm 28 is depressed. The swinging end of the arm 25 is connected by a spring 31 with the fixed framework of the machine at 32.

When the parts are in the position shown by the full lines in Fig. 3, the arm 28 is raised and the rolls 30, 30 depressed, allowing the weight of the wire drawing block 2 to carry it down to engage the clutching members between the block and the vertical driving shaft 4. In this position the pivot 33 is held to the right of a straight line passing from the center of the treadle shaft 16 to the center of the pivot 33, with the end 19 of the foot treadle 17 resting against the fixed stop 20 and locking the arm 25 against the pulling tension of the spring 31.

By depressing the end 23 of the foot treadle sufficiently to carry the pivot 21 to the left of a straight line joining the center of the shaft 16 and the pivot 33, the spring 31 will be allowed to act to carry the arm 25 into the position shown by the broken lines 25^b, bringing the bent link 26 into the position shown by the broken lines 26^a and depressing the arm 28 into the position shown by the broken lines 28^a, causing the wire drawing block 2 to be lifted out of engagement with its clutching mechanism.

In the position of the parts indicated by broken lines in Fig. 3, the pivotal connections between the opposite ends of the bent link 26 at 34 and 35 will lie in a straight line passing slightly to the left of the center of the pivot 25^a, thereby locking the parts against movement by the weight of the wire block 2 as it is held in a raised position on the rolls 30, 30.

I claim,

1. In a wire drawing machine comprising a rotatable wire drawing block, a driving mechanism and clutching members between said driving mechanism and said rotatable block, of mechanism for separating said clutching members, comprising a foot treadle and a toggle-joint connection between the foot treadle and the clutching mechanism.

2. The combination with a rotatable wire drawing block, of clutching members for connecting said block with the driving power, and mechanism for disconnecting

said clutching members, comprising a toggle-joint, and means for throwing the members of said toggle-joint past their centers at will.

3. The combination with a wire drawing block and a clutching mechanism between said block and the driving power, of mechanism for engaging and disengaging said clutching mechanism, consisting of a swinging yoke, a rocking shaft provided with a foot treadle, and a toggle-joint connection between said rocking shaft and said yoke.

4. The combination with a rotatable wire drawing block and a clutching mechanism for connecting said block with the driving power, of clutch disengaging mechanism comprising a toggle-joint, means for throwing the members of said toggle-joint past their centers at will, and a spring with its tension applied to actuate said toggle-joint in disengaging said clutching mechanism.

5. The combination with a rotatable wire drawing block and a clutching mechanism for connecting said block with the driving power, of a clutch disengaging mechanism, consisting of a swinging yoke, a rocking shaft provided with a foot treadle, a toggle-joint connection between said yoke and said rocking shaft, and a spring with its tension applied to actuate said toggle-joint connection in disengaging said clutching mechanism.

6. The combination with a rotatable wire drawing block and clutching members between said block and the driving power, arranged to be brought into engagement by gravity, of a clutch disengaging mechanism, consisting of a swinging yoke for lifting one of the clutching members out of engagement with the other clutching member, an arm projecting from said yoke, a rocking shaft, a radial arm carried by said shaft, a link pivotally connecting said arms, a foot treadle for rocking said shaft at will, and a spring with its tension applied to the clutch disengaging mechanism to lift one of the clutching members against gravity.

7. The combination with a rotatable wire drawing block and a clutching mechanism therefor, of a yoke for lifting one of the clutching members out of engagement with the other clutching member, a toggle-joint connection with said yoke, a stop for limiting the movement of said toggle-joint in one direction, a spring for actuating said toggle-joint connection, and means for moving said toggle-joint past its centers at will.

8. In a wire drawing machine, a clutch, a swinging yoke, an arm pivoted to the frame, a link between said arm and yoke, a toggle-joint for actuating said arm, and a spring with its tension applied to disengage the clutch.

9. In a wire drawing machine, comprising a rotatable wire drawing block, a driving

mechanism and clutching members between said driving mechanism and said rotatable block, a yoke for separating said clutching members, an arm pivoted on the frame-

5 work, a link connecting said arm and said yoke, a spring with its tension applied to disengage the clutching members, a rocking shaft, a foot treadle carried by the rocking shaft, and a toggle-joint connection between

the rocking shaft and said arm to reverse the 10 action of said spring.

Dated this twenty-fifth day of August 1909.

ELBERT H. CARROLL.
